Benfrey Dress Co., Inc., a corporation of New

Application November 14, 1935, Serial No. 59,556

Term of patent 3½ years

To all whom it may concern:

Be it known that I, Ada Dallanegra, a citizen of the United States, residing at 42-17 64th Street, Woodside, Long Island, county of Queens, city and State of New York, have invented a new, original, and ornamental Design for an Ensemble Dress, of which the following is a specification, reference being had to the accompanying drawing, constituting a part thereof.

Figure 1 is a front elevation of an ensemble dress, showing my design, and

Figure 2 is a front elevation of the dress unit of the ensemble, shown in Figure 1.

Figure 3 is a rear elevation of the ensemble dress, shown in Figure 1.

The dress section of the rear of the garment follows the lines of the front.

The characteristic feature of my design resides in the provision of a series of bands of embroidery and drawn work around the sleeves of the jacket and on the front of the dress bodice as shown.

I claim:

The ornamental design for an ensemble dress, substantially, as shown and described.

In testimony whereof, I have hereunto subscribed my name this 9th day of November, 1935.

ADA DALLANEGRA.
